ABSTRACT: An elongated cylindrical pressure vessel has a longitudinally extending door in the cylindrical wall of the vessel, through which a carpet can be introduced or removed. A bolt for securing the door is divided into at least three axially aligned portions each of which is wholly receivable in a socket in which it is also axially movable, at least one of such sockets being secured to the door, and at least one of such sockets being secured to the vessel. The bolt portions are movable in unison between a position in which each bolt portion is wholly received in its socket and a position in which at least two bolt portions are engaged both in a socket secured to the door and in a socket secured to the vessel.

DEVICE FOR DYEING OR WASHING CARPETS

BACKGROUND OF THE INVENTION

This invention relates to a device for dyeing or washing carpets at high temperatures in an elongated cylindrical pressure vessel having a door for insertion and extraction of the carpet, the door being securable by a bolt.

In known devices the door of the pressure vessel is secured by a long bolt, but the insertion and release of this require considerable space. There are also frequent difficulties in inserting long closure bolts.

SUMMARY OF THE INVENTION

The main object of the invention is to provide a device of the type described which avoids these disadvantages, so that only a very small space is needed for inserting and releasing the bolt, and the closure joint is easy to make and release.

According to the invention this object is achieved in that the bolt is divided into at least three portions which can be moved axially in unison, so that in one end position each bolt portion is in engagement only with the pressure vessel or with the door, while in the other end position at least two bolt portions are in engagement with both the pressure vessel and the door.

According to a desirable further development of the invention, the door extending over almost the whole length of the vessel lies on the cylindrical periphery of the vessel. The forces produced by the pressure in the vessel are thus supported directly by the door material, and the bolt closure device is substantially freed of pressure.

BRIEF DESCRIPTION OF THE DRAWINGS

FIG. 1 is a schematic cross section through a dyeing device 35 in accordance with the invention;

FIG. 2 is a view of the device from the front;

FIG. 3 is a section on line III—III of FIG. 2;

FIG. 4 is a detail of FIG. 1;

FIG. 5 is a cross section through the bolt device for securing the door of the vessel; and

FIG. 6 is a section corresponding to FIG. 5 with the bolt closed.

DESCRIPTION OF THE PREFERRED EMBODIMENT

The elongated pressure vessel 1 seen in FIGS. 1 and 2 is used for dyeing or washing carpets across their whole width at high temperatures. In the vessel 1 there are provided for example a driven drum 2 and support and guide rollers 3 which maintain the carpet 4 travelling through the treatment bath 5.

The pressure vessel 1 has a door 6 extending over almost the whole length of the vessel, with its upper long side 7 hingedly connected to the vessel wall and its lower long side 8 lockable to the wall of the vessel by a bolt device which will be explained in more detail with reference to FIGS. 5 and 6.

As shown schematically in FIG. 1, door 6 when in the closed condition lies exactly on the peripheral line of the vessel.

FIG. 4 shows the arrangement of a seal 9 for sealing the door 6 and vessel 1 (for example at the lower longitudinal side 8). The seal is disposed within the cylindrical peripheral line of the vessel 1, on which the door is located, is indicated by reference 12. The sealing at the joints of the other three sides is made in the same manner.

At the ends of the vessel aperture to be closed by the door 6 are provided two supports 13, 14 joined together by tie rods 15 running longitudinally of the vessel aperture. The disposition of these supports and the positions of the tie rods are shown in detail in FIG. 3.

As indicated in FIG. 3, the vessel is somewhat cut away in the area of support 14 (the same applies for the other support 13); support 14 is thus let in to vessel 1 to some extent. The line joining the two tie rods 15 is indicated by reference 16 in

FIG. 3. According to the invention this connecting line 16 coincides with the centroidal axis of support 14.

In FIG. 3 there are also shown two points A and B, which lie on the two longitudinal sides of the vessel aperture. Together with the line 17 joining them, these points A and B define a segment of a circle determined by the vessel aperture. The centroidal axis of this segment is indicated at C. According to the invention this centroidal axis also lies on the line 16 connecting the two tie rods 15 (and therefore also lies on the centroidal axis of support 14).

This construction ensures that the supports 13 and 14 can absorb the forces caused by internal pressure in the container in the area of the ends of the vessel aperture (i.e. where there is no casing sheet to absorb the forces) in such manner that no appreciable bending or torque forces are applied to the supports. The two supports may consequently be of relatively small dimensions.

The door 6, sealed on all four sides, which is hingedly connected to the vessel along its upper long side 7, can be bolted to the vessel at its lower long side 8. The door is however free at the two ends, adjacent supports 13 and 14. In this way there is produced a statically determined system, which simplifies the dimensioning.

The bolting of door 6 to the vessel 1 (adjacent the lower long side 8 of door 6) is shown in detail in FIGS. 5 and 6.

Door 6 is provided with weblike projections 25, while the vessel 1 has corresponding weblike projections 26 laterally offset from the projections 25 on door 6.

The projections 25, 26 have support sockets 27 wherein are movably housed bolt portions 28a, 28b—28n. With the exception of the two end bolt portions 28a, 28n the length of these bolt portions corresponds generally to the distance between the centers of adjacent projections 25, 26.

Adjacent each end of the bolt device formed by the bolt portions 28a—28n there is disposed a simply acting operating means, which engages the bolt device axially. The two operating means are schematically represented by the arrows 29, 30 in FIGS. 5 and 6.

When the bolt device is in the left-hand end position shown in FIG. 5, each bolt portion is in engagement with only one of the two elements (vessel 1 and door 6) to be joined. The bolt portion 28b for instance is only in engagement with the weblike projection 25 of door 6 while the next bolt portion 28c only forms a positive joint with the weblike projection 26 of vessel 1. In this position of the bolt device, the door can readily be tilted about its support line (the upper long side 7, see FIG. 1) and the vessel therefore opened.

If the bolt device shown in FIGS. 5 and 6 is to be locked and door 6 thus firmly connected to vessel 1, an axial pressure is exerted on the bolt device by the left-hand operating means (arrow 29), so that the bolt portions 28a—28n move into their right-hand end position. This position is determined by the foremost bolt portion 28n abutting against a stop 31. As seen from FIG. 6, in this right-hand end position each bolt portion (apart from portion 28n) is in engagement with both the elements to be joined (vessel 1 and door 6); bolt portion 28b for instance is thus positively connected both with projection 25 on door 6 and projection 26 on vessel 1.

The bolted joint can therefore be closed or opened by a relatively small axial displacement of the bolt device. Opening is effected in a corresponding manner, with the right-hand operating means (arrow 30) pushing the bolt device into its left-hand end position. The latter is determined by bolt portion 28a abutting against a stop 32.

The two operating means indicated by arrows 29 and 30 may for instance comprise pneumatic or hydraulic pressure cylinders.

The operating means (arrows 29 and 30) may instead consist of screw spindles. This simpler mechanism is adequate for cases (e.g. the pivotal mounting of door 6), wherein the bolted joint is usually made only once and released only in rare instances.

In order to prevent the bolt portions falling out of the projections 25, 26 when door 6 is open, the bolt portions are preferably mounted in these projections in such a manner that they can only make the axial movements needed to bolt and unbolt the door.

The ends 33 of the individual bolt portions 28a—28n, which come into contact with adjacent bolt portions, are rounded, preferably with a part-spherical shape and/or a marked marginal chamfer. This ensures that adjacent bolt portions can move readily against each other i.e. without much friction, while the door is being opened and shut. It also ensures easy introduction of the bolt portions into the weble like projections 25, 26 during closing of the operating means 29.

We claim:

1. A device for dyeing or washing carpets at high temperatures, comprising an elongated cylindrical pressure vessel having a longitudinally extending door in the cylindrical wall of the vessel, through which a carpet can be introduced or removed, wherein the improvement comprises a bolt for securing the door, which is divided into at least three axially aligned portions each of which is wholly receivable in a socket in which it is also axially movable, at least one of such sockets being secured to the door, and at least one of such sockets being secured to the vessel, the bolt portions being movable in unison between a position in which each bolt portion is wholly received in its socket and a position in which at least two bolt portions are engaged both in a socket secured to the door and in a socket secured to the vessel, the door being a section of a cylinder and coinciding in its closed position with the axis of

each of the sockets and with the cylindrical wall of the vessel.

2. A device according to claim 1 wherein means for engaging and axially displacing the divided bolt are provided adjacent each end of the divided bolt.

3. A device according to claim 1 wherein the contacting ends of the bolt portions are rounded.

4. A device for dyeing or washing carpets at high temperatures, comprising an elongated cylindrical pressure vessel having a longitudinally extending door in the cylindrical wall of

10 the vessel, through which a carpet can be introduced or removed, wherein the improvement comprises supports secured to the vessel which extend around the periphery of the vessel along opposite ends of the door and are connected by tie rods extending longitudinally of the vessel, a bolt for securing

15 the door, which is divided into at least three axially aligned portions each of which is wholly receivable in a socket in which it is also axially movable, at least one of such sockets being secured to the door, and at least one of such sockets being secured to the vessel, the bolt portions being movable in unison between a position in which each bolt portion is wholly received in its socket and a position in which at least two bolt portions are engaged both in a socket secured to the door and in a socket secured to the vessel.

20 5. A device according to claim 4 wherein the supports have a common centroidal axis which coincides with the centroidal axis of a segment of a circle defined by the door and which lies in a plane passing through two tie rods connecting the supports.
